UNITED STATES PATENT OFFICE.

SIDNEY H. RING, OF CLATSKEANIE, OREGON.

MUSIC-HOLDER.

1,269,859.

Specification of Letters Patent. Patented June 18, 1918.

Application filed June 13, 1917. Serial No. 174,558.

To all whom it may concern:

Be it known that I, SIDNEY H. RING, a citizen of the United States, residing in Clatskanie, county of Columbia, and State 5 of Oregon, have invented certain new and useful Improvements in Music-Holders, of which the following is a specification.

My invention relates to music holders, and more particularly to a combination sheet 10 music holder and case, into which a number of sheets of music can be placed in a flat condition and held for protection, and also for use, my holder being adapted to open up in a flat manner and to be placed upon a 15 piano rack, or other music support with the music in position for use.

In order to clearly explain my invention I have illustrated one practical embodiment thereof in the accompanying sheet of drawings, which I will now describe.

Figure 1 is an open view of a music holder embodying my invention;

Fig. 2 is a lower end view thereof; and

Fig. 3 is a perspective view thereof, in 25 closed form.

Referring now in detail to the drawings, my invention comprises two box-like cover members 1 and 2, hinged at their adjacent sides to a back 3, by means of double hinges 30 4-4, said hinges being provided with holding prongs 5-5, on which sheets of music 6, can be placed, as indicated. Mounted near each of said hinges 4-4, on the cover 1, is a punch 7, spaced at the right distance so 35 that when a sheet of paper is inserted therein and said punches are pressed, holes at the right distance apart will be punched in the sheet music, whereupon said music can be placed upon said holding prongs 5-5.

40 The covers 1 and 2 are provided along the outer and top sides with flange-like members 1^a-1^a and 2^a-2^a, adapted to meet edge-wise when said cover members 1 and 2 are closed together, as shown in Fig. 3. On 45 their lower sides said cover members are provided with music supporting ledges 8 and 9, adapted to overlap each other, as shown in Fig. 3, when the music holder is closed. A latch spring 10 may be provided 50 on the flange member 1^a, and adapted to engage with a locking stud 11, on the flange member 2^a, when the cover members are closed together. A handle 12, is provided 55 on the back 3, whereby said case can be carried, thus providing a convenient means for carrying said music holder.

While I have illustrated one practical embodiment of my invention, slight changes can be made therein without departing from the spirit thereof, and I do not, therefore, 60 limit the invention to the exact details here shown, except as I may be limited by the hereto appended claims.

I claim:

1. A combination music holder comprising 65 two box-like cover members, means hinging the same together, whereby they can be closed one upon the other in box-like form, arched holding prongs spaced apart at the hinged joint to receive the music, punching 70 devices arranged opposite each of said prongs on one of said cover members, whereby to punch holes in the music at a space apart corresponding to the space between said prongs, said cover members being provided 75 on their lower edges with projecting ledge members adapted to act as supports for the lower end of music placed therein, substantially as described.

2. A combination music holder and rack 80 comprising two cover members of box-like form having meeting flange-like members around their inner faces at their upper and outer edges, a back member to the opposite edges of which said cover members are 85 respectively hinged, whereby to be opened out flatwise into substantially the same plane of said back member, arched holding prongs mounted on said back member between said cover members and adapted to receive sheet 90 music, whereby the same can be turned from one cover member to the other, said cover members having overlapping projecting ledge members on their lower ends adapted 95 to act as supports for the lower ends of sheet music placed on said prongs when said holder is open substantially as described.

3. A combination music holder and rack comprising two cover members of box-like form, a back member to the opposite edges 100 of which said cover members are respectively hinged, whereby to be opened out flatwise into substantially the same plane of said back member, arched holding prongs mounted on said back member between said 105 cover members and adapted to receive sheet music, whereby the same can be turned from one cover member to the other, said cover members having projecting ledge members on their lower ends adapted to act as supports 110 for the lower ends of sheet music placed on said prongs, and a hole punching

device mounted on one of said cover members opposite each of said holding prongs and at the same space apart, and adapted for punching holes through sheet music to be placed in said holder, substantially as described.

4. A combination music holder and rack comprising two cover members provided at their outer and top sides with flange-like members, a back member to the opposite edges of which said cover members are hingedly attached and adapted to open out flatwise into substantially the same plane, holding prongs mounted on said back member at a space apart and adapted to have sheet music mounted thereupon, punching devices mounted on one of said cover members opposite said prong members and at

the same space apart and adapted for punching holes through music sheets to receive said prongs, said cover members being provided at their lower edges with projecting music supporting ledges, adapted to overlap each other when said cover members are closed together in box-like form, the flange-like members and the music supporting ledges on said cover members forming edge walls, whereby to wholly inclose said music when said cover members are closed together, substantially as shown and described. 25 30

Signed at Clatskanie, Columbia county, Oregon, this 28 day of May, 1917.

SIDNEY H. RING.
